(57) **CLAIM**

The ornamental design for a heated glove, as shown and described.

DESCRIPTION

FIG. 1 is a perspective view of a heated glove showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and, FIG. 10 is an enlarged view of portion 10 shown in FIG. 2. The dot-dash broken lines represent the boundary of the enlarged portions and form no part of the claimed design. The short thick evenly spaced broken lines in the drawings depict stitching and form no part of the claimed design. The long thin evenly spaced broken lines in the drawings depict portions of the heated glove that form no part of the claimed design.

1 Claim, 10 Drawing Sheets
